CHILD'S APRON

Joseph Baxter Roberts, Tenafly, N. J.

Application September 1, 1953, Serial No. 26,656

Term of patent 3½ years

(Cl. D3—26)

To all whom it may concern:

Be it known that I, Joseph Baxter Roberts, a citizen of the United States, residing at Tenafly, in the county of Bergen and State of New York, have invented a new, original, and ornamental Design for a Child's Apron, of which the following is a specification, reference being had to the accompanying drawing, forming a part hereof.

Fig. 1 is a front elevation of the child's apron in the extended position, showing my new design.

Fig. 2 is a side view of the apron shown in Fig. 1.

I claim:

The ornamental design for a child's apron, as shown.

JOSEPH BAXTER ROBERTS.
